US00D643115S

(12) **United States Design Patent**
Gonzales et al.

(10) **Patent No.:** US D643,115 S
(45) **Date of Patent:** ** Aug. 9, 2011

(54) **INSERTION DEVICE**

(75) Inventors: **Donald A. Gonzales**, San Antonio, TX (US); **Fred B. Dinger, III**, San Antonio, TX (US); **Jeffrey S. Wrana**, San Antonio, TX (US)

(73) Assignee: **Entrigue Surgical, Inc.**, San Antonio, TX (US)

(**) Term: **14 Years**

(21) Appl. No.: **29/363,134**

(22) Filed: **Jun. 4, 2010**

(51) LOC (9) Cl. **24-02**

(52) U.S. Cl. **D24/133**

(58) **Field of Classification Search** D24/133, D24/143, 145, 146; 606/83, 99; 600/114
See application file for complete search history.

(57) **CLAIM**

The ornamental design for an insertion device, as shown and described.

DESCRIPTION

FIG. 1 is a front perspective view of an insertion device showing our design.

FIG. 2 is a back perspective view thereof;

FIG. 3 is a back view thereof;

FIG. 4 is a front view thereof;

FIG. 5 is a left side view thereof;

FIG. 6 is a top view thereof; and,

FIG. 7 is a bottom view thereof.

The dashed lines in FIGS. 1-7 represent environmental structure and form no part of the claimed design.
